UNITED STATES PATENT OFFICE.

JOHN F. ERVIN, OF MOLINE, ILLINOIS, ASSIGNOR TO DEERE & COMPANY, OF MOLINE, ILLINOIS, A CORPORATION OF ILLINOIS.

SAND HANDLING AND CUTTING APPARATUS.

1,323,461.

Specification of Letters Patent.

Patented Dec. 2, 1919.

Application filed November 4, 1914. Serial No. 870,296.

To all whom it may concern:

Be it known that I, JOHN F. ERVIN, a citizen of the United States, residing at Moline, in the county of Rock Island and 5 State of Illinois, have invented certain new and useful Improvements in Sand Handling and Cutting Apparatus, of which the following is a specification, reference being had therein to the accompanying drawings.

10 This invention relates to sand working machines, particularly to those of the class used in foundries, and such other places where sand is employed as a molding medium, for "cutting", that is breaking up and thoroughly mixing, sand that is to be used in a molding operation and delivering the sand to a predetermined place in 15 condition for use.

20 To prepare sand for use in making molds it is first moistened or "tempered". Following that it is "cut", which consists of thoroughly working or mixing the sand to break up all lumps that may be present and to spread the moisture evenly, putting 25 the sand in a loose, mellow condition and of uniform consistency.

25 My invention has for its object to provide a simple and efficient machine, capable of rapidly "cutting" or preparing sand for 30 molding purposes.

Figure 1 is a side elevation of the improved machine.

Fig. 2 is a top plan view of the same.

35 Fig. 3 is a view of the cylinder like "cutting" device, which consists of a series of blades supported by two outside spiders and one central spider.

40 Fig. 4 is the central blade supporting spider, and

Fig. 5 represents one of the outside blade supporting spiders.

In the form in which I have illustrated 45 the invention, two floors are employed to carry out certain features of the invention, the top floor, designated by the numeral 1 being the working floor or the floor upon which the molds and castings are made. After the molds are broken up the sand of which they were composed is shoveled 50 through an opening in the floor into the hopper 2 and later dropped through the chute 3 onto the second or lower floor 4. Upon this floor 4 it may be moistened for 55 tempering as found necessary.

Whenever it is desired to work the sand

and make it ready for use, an operator, stationed on the lower floor 4, shovels the sand into the hopper 5, and, falling upon the rapidly rotating cylinder 6, it is broken up and mixed into a proper consistency, all 60 of the lumps being broken up.

The cylinder is of a peculiar construction. It consists of three blade supporting spiders 7, 8 and 9, two of them (7 and 9) serving as outside supports and the other 65 (8) serving as a central support. The blades themselves, indicated by the numeral 10 are mounted on the arms of the supporting spiders and they are inclined backward from the sides toward the center. 70 The inclination of the blades throws the sand at an angle to the direction of rotation of the cylinder, insuring a thorough mixture of the sand and also prevents the sand from working to the ends of the cylinder 75 and there accumulating so as to obstruct its action. In the construction shown the blades extend outward along radial lines, and they should in all cases be at least approximately radial; that is to say, they 80 should not depart from the radial arrangement enough to prevent them acting upon the sand in substantially the manner hereinafter described. The cylinder is driven by a motor 10a.

85 The cylinder is inclosed in the casing 11 having a feed opening at 12 in its upper side near the level of the floor 4, and a lateral discharge opening 13 in the rear. The sand is guided onto the cylinder by the inclined 90 wall 14, and the top wall 15 of the casing serves as a breaker plate and as a deflector for guiding the material out through the discharge opening 13.

95 The peripheral velocity of the cylinder is such as to throw the sand in a spray through the opening 13, where much of it is caught by the conveyer buckets 16 of the conveyer 17, which is driven by a motor 18. The sand which does not initially enter the buckets drops onto the floor of the pit 19 where it is scooped up by the conveyer buckets 16 as they begin their upward flight.

105 The conveyer is preferably constructed and arranged to intercept the flying sand forcibly thrown from the breaking cylinder so that the impact of the material is utilized to break up any lumps not already reduced. To this end the inner wall 16a of each conveyer bucket is made relatively 110

high while the outer wall is relatively low, so that the forcibly projected material strikes the upstanding inner wall 16^a and falls to the bottom of the bucket.

5 The conveyer 17 carries the sand from the pit 19 up and delivers it onto the working floor 1 where it is ready to be used again for molds.

It will be seen that I have provided a simple system of devices whereby the sand after being once used for molds can be entirely removed from the molding floor and all of it subjected to a uniform treatment whereby it is restored to the proper working condition. And the parts are so arranged that the sand is treated rapidly and with a minimum amount of manual handling. After the castings have been removed from the molds the sand can be pushed or shoveled into the hopper 2 from where it falls onto the floor 4 where it can be moistened. Then from this floor it can be easily shoveled into the feed opening 5 of the casing onto the cylinder. The sand falls directly onto the blades of the rapidly revolving cylinder so that it is driven violently and at an angle either against the breaker plate 15 or directly out through the discharge opening 13. Ultimately all of the sand, whether first striking the plate 15 or not, passes out through the opening 13 and into the path of the conveyer buckets 16, because sand that only grazes the plate 15 continues its flight through the discharge opening while sand that strikes said plate somewhat squarely falls to be again struck by the cylinder blades and projected through the discharge opening. A part of the sand is caught directly by the buckets and carried upward and the remainder falls to the bottom of the pit 19 where it is engaged by the buckets and lifted. The buckets carry the sand upward through the opening in the floor 1 and finally deliver it onto the said floor where it is ready for use. The extended inner walls 16^a of the buckets serve advantageously in discharging the sand, as will be apparent from an inspection of Fig. 1.

50 What I claim is—

1. In apparatus for working molder's sand, the combination of a horizontally arranged rotating cylinder having relatively wide elongated blades, respectively positioned to have their longitudinal lines extend from the ends of the cylinder inward toward the center, with their wide faces exposed forward in the direction of rotation, and a casing surrounding the cylinder having a fuel opening in its top side arranged to deliver the sand to the blades when they

are rising upward, a discharge opening in its rear side, both said openings extending from end to end of the cylinder and an interior breaker plate above the cylinder 65 and at said discharge opening, whereby sand entering through the feed opening is struck by the upwardly rising cylinder blades and forcibly thrown through the said discharge opening, either directly or after impact 70 against the said breaker plate.

2. In apparatus for working molder's sand, the combination of a horizontally arranged rotating cylinder having relatively wide elongated blades, respectively positioned to have their longitudinal lines extend from the ends of the cylinder inward toward the center, with their wide faces exposed forward in the direction of rotation, and a casing surrounding the cylinder 80 having a feed opening in its top side arranged to deliver the sand to the blades when they are rising upward and a discharge opening in its rear side, said rear opening extending from end to end of the 85 cylinder opposite to the upper part of the same, said casing having a top breaker surface at said discharge opening, whereby sand entering through the feed opening is struck by the upwardly rising cylinder 90 blades and forcibly thrown through the said discharge opening, either directly or after impact against the said breaker surface.

3. In apparatus for working molder's sand, the combination of a horizontally arranged rotating cylinder having relatively wide elongated blades, respectively positioned to have their longitudinal lines extend from the ends of the cylinder inward toward the center, with their wide faces exposed forward in the direction of rotation, the inner ends of said blades being declined forwardly, and a casing surrounding the cylinder having a feed opening in its top side arranged to deliver the sand to the 100 blades when they are rising upward and a discharge opening in its rear side, said rear opening extending from end to end of the cylinder opposite to the upper part of the same, said casing having a top breaker surface at said discharge opening, whereby sand entering through the feed opening is struck by the upwardly rising cylinder 105 blades and forcibly thrown through the said discharge opening, either directly or after impact against the said breaker surface.

In testimony whereof I affix my signature, in presence of two witnesses.

JOHN F. ERVIN.

Witnesses:

JESSIE SIMSER,
W. G. DUFFIELD.

(over)

It is hereby certified that in Letters Patent No. 1,323,461, granted December 2, 1919, upon the application of John F. Ervin, of Moline, Illinois, for an improvement in "Sand Handling and Cutting Apparatus," an error appears in the printed specification requiring correction as follows: Page 2, line 60, claim 1, for the word "fuel" read *feed*; and that the said Letters Patent should be read with this correction therein that the same may conform to the record of the case in the Patent Office.

Signed and sealed this 30th day of November, A. D., 1920.

[SEAL.]

L. B. MANN,

Acting Commissioner of Patents.
